UNITED STATES PATENT OFFICE.

MORTON HAVENS, JR., OF ALBANY, NEW YORK.

DESIGN FOR A BRANCH BOX FOR INSULATED ELECTRIC WIRES.

No. 39,708.

Specification for Design.

Patented Dec. 22, 1908.

Application filed February 16, 1906. Serial No. 301,513. Term of patent 7 years.

To all whom it may concern:

Be it known that I, MORTON HAVENS, Jr., a citizen of the United States, residing and having my post-office address at No. 79 Chapel street, in the city of Albany, county of Albany, and State of New York, have invented a new, original, and ornamental Design for a Branch Box for Insulated Electric Wires.

In the accompanying drawing, Figure 1 is a perspective view of a branch box for insulated electric wires, embodying my design, and Fig. 2 is a perspective view of said branch box shown as inverted.

As shown my design embodies a short pipe-like section merging at one end by curves into a transverse box-like portion of symmet-

rical size and shape which curves from the end of said pipe-like section towards its opposite side which has thereon a cover plate conforming in shape to the outline of the portion upon which it fits. The box-like portion is of substantially the same thickness as the pipe-like section and has curved tops and ends.

What I claim is:—

The ornamental design for a branch box for insulated electric wires, substantially as herein shown and described.

MORTON HAVENS, JR.
